SECTIONAL DERRICK

Walter Brauer, Oklahoma City, Okla.

Application August 5, 1939, Serial No. 288,661.

3 Claims. (Cl. 189—15)

This invention relates to a sectional derrick, and more particularly, but not by way of limitation, to a derrick for use in connection with a portable rotary rig structure for oil well drilling.

In the past few years shallower oil formations have been discovered which have caused adaptation of lighter rotary drilling outfits for drilling these formations. With the advent of the portable rotary drilling rig, there has been an adaptation of structures that could be easily moved and rigged up, and one essential part of the rig is a portable derrick capable of such adaptation.

It is therefore an important object of this invention to provide a derrick composed of a plurality of sections of upwardly decreasing dimensions, said sections being capable of being easily collapsed or folded into a compact space, and when assembled together form a rigid upright derrick for use with a well drilling rig.

Another object is to supply a derrick which may be easily assembled and disassembled for facilitating transportation from place to place.

A further object is to furnish a derrick of substantially angled iron construction comprising three sections, with the middle section hingedly connected to both the top and bottom of the lower section in such manner to be capable of optional swinging, either forward or backward, in order to fold the derrick as may be desired.

And still another object is to produce a sectional derrick for use with a portable rig unit, said derrick constructed in such manner to allow disassembly of the derrick for facilitating movement of the derrick in conjunction with the skid for short hauls, as well as disassembly of the derrick for separate transportation of the derrick apart from the rig.

Another object is to provide a sectional derrick for use with a portable drilling unit capable of being assembled and disassembled by its own drilling unit, thus eliminating any additional equipment for this purpose.

And an additional object is to provide a sectional derrick for use with a portable rotary rig formed substantially of angle iron welded together in order to provide lighter weight, the sections when assembled to form a rigid, durable and practically indestructible derrick which will not materially deteriorate through wear, use or inclemency of the weather.

Other objects and advantages of the invention will be evident from the following detailed description read in conjunction with the ac-

companying drawings which illustrate one form of my invention.

In the drawings:

Fig. 1 is a side elevation of the derrick in complete assembly.

Fig. 2 is a partial elevation of the derrick taken from the open side thereof.

Fig. 3 is a front elevation of the lower section of the derrick.

Fig. 4 is an elevational view of the derrick mounted on a draw-works skid, showing the upper sections swung in one direction.

Fig. 5 is a view similar to Fig. 4 showing the upper sections of the derrick swung in another direction.

Fig. 6 is a side elevational view of the lower section of the derrick.

Fig. 7 is a similar view of the middle section of the derrick.

Fig. 8 is a detail view in front elevation showing the hinge connection at the upper end of the lower section of the derrick.

Fig. 9 is a side elevation thereof.

Fig. 10 is a side elevation in detail of the hinge connection at the bottom end of the lower section of the derrick.

Fig. 11 is a front elevation thereof.

Referring more particularly to the drawings in detail, the derrick comprises a plurality of separable sections divided from each other vertically and constructed convergently upward, each section being substantially of the same dimensions at its base as the next lower section is at its apex.

35 The lowermost section is designated as A, the middle section as B, and the upper or top section as C.

Referring to each of the sections separately, and more particularly the lower section A, this section comprises four corner posts, 2, 4, 6 and 8, with the posts 2 and 4 being substantially greater in length than the posts 6 and 8. The derrick posts are formed of angle iron in order to provide greater strength with a minimum of weight to the derrick.

The lower end of each of the corner posts of section A are provided with annular flanges 10 in order to secure the section (preferably by bolting) to a derrick floor or skid 12 (note Fig. 5).

Referring to Figs. 3 and 6, on three sides the corner posts 2, 4, 6 and 8 are rigidly connected by a plurality of horizontal cross ties 14 formed of angle iron and preferably welded to the posts. The corner posts are additionally braced by a

plurality of diagonal braces or ties 16 cooperating with the cross ties 14 for connecting the posts. It will be noted that the lower part of the section A is constructed with inclined braces 18 in order to provide openings in this portion of the derrick for a purpose as will be hereinafter set forth.

The posts 2 and 6, as well as 4 and 8, are likewise connected by a pair of parallel bars 20 diagonally disposed and welded to the extreme 10 top of the posts.

The corner posts 2 and 4 are each provided with identical hanger posts 22 comprising upright socket members 24 and 26 integrally secured to the posts. A stationary shaft 28 is secured in the members 24 and 26, and supports a pair of freely rotatable pulleys 30 for a purpose as will be hereinafter set forth.

It will be understood that each of the corner posts 2 and 4 are provided with a hanger post 22. However, for the purpose of illustration, only one hanger post will be considered, as is clearly shown in Figs. 8 and 9. The socket members 24 and 26 are provided with an aligned aperture 32 for receiving a bolt 34 held in the apertures by nuts 36 for a purpose as will be hereinafter set forth.

The shorter posts 6 and 8 of section A are each provided with an integral hanger post 42, and as clearly shown in Figs. 10 and 11, each post comprises a pair of upstanding apertured members 44 and 46 receiving a bolt 48 secured by the nuts 50, for a purpose as will be hereinafter set forth.

From the foregoing it will be apparent that the lower section A is substantially in the shape of a 30-60 degree triangle with the diagonal braces 20 forming the hypotenuse of the triangle.

Referring to Figs. 1 and 7, the middle section B comprises corner posts 52, 54, 56 and 58, with the posts 52 and 54 substantially greater in length than the posts 56 and 58. The lower end of the posts 56 and 58 are connected to the lower end of the corner posts 52 and 54 by a pair of parallel, diagonally disposed bars 60 complementary to the bars 20 in the lower section A. On three sides, the corner posts of section B are rigidly supported by a plurality of horizontally disposed cross ties 62 cooperating with a plurality of diagonally disposed braces 64, all formed of angle iron and welded to their respective corner posts. The lower end of each of the posts 52 and 54 are provided with an identical hanger post 66 comprising apertured members 68 and 70 integrally secured to the posts. The lower portion of the members 68 and 70 are provided with aligned apertures in order that the bolt 48 may be received therein. A stationary shaft 72 is secured in the hanger posts 66, and has mounted thereon a plurality of freely rotatable pulleys 74.

From the foregoing, it will be apparent that the hanger posts 42 and 66 form a hinge connection between the legs 6 and 8 of lower section A and the legs 52 and 54 of upper section B, which facilitates assembly and disassembly of the section B with respect to the section A, as will be hereinafter set forth.

The lower ends of each of the corner posts 56 and 58 are provided with an apertured hanger post 76 which cooperates with the members 24 and 26 and bolt 34 in order to provide a hinged connection at this point between the lower section A and the upper section B. The upper end 70 of each of the corner posts 52, 54, 56 and 58 of

the section B are provided with a plurality of bolt holes 78 for a purpose as will be hereinafter set forth.

From an inspection of Fig. 2, it will be noted that one side of sections A and B are open due to the elimination of their respective cross bars and the supporting braces. A projection bar or rack member 80 is welded to the corner posts 52 and 54 on the open side which provides for racking up single sections of drill pipe (not shown) during the drilling operation.

The upper section C (Fig. 1) comprises four identical corner posts 82 being formed of angle iron and rigidly inter-connected by cross bars 84 and intersecting ties 86. The extreme upper end of the section C is provided with cross bars 88 of increased height for supporting a shaft 89 and crown block 90 in any conventional manner for a purpose as will be hereinafter described. The lower end of each of the corner posts 82 is provided with a fish plate or angle bar 92 having a plurality of apertures 94. It will be apparent that with the section C in upright position, with respect to section B, that the apertures 94 are in alignment with the apertures 78 for receiving bolts 96 securing the sections together. From an inspection of Fig. 1, it will be noted that with the derrick in upright position, the section C is bolted to the section B, and in turn, section B is bolted to section A, through the hinge connections provided by the cooperative hanger posts.

Referring now to Fig. 4 showing the disassembly of the derrick by folding sections B and C in one direction with respect to section A, the cable 98 of the rotary drawworks 100 extends upwardly from the drawworks through the interior of the derrick and passes over a pulley 30 on a shaft 28 and around the crown block 90, downwardly through the derrick and over a pulley 74 and through the travelling block 102. The hook portion of the block 102 is secured to the skid 12 and from the block 102 the cable continues upwardly over a second pulley 74, and again through the crown block 90, and back through the derrick over the shaft 72 to be fixed with a dead end to the skid 12. With this arrangement, it will be apparent that any rotation of the drawworks 100 will obviously cause a movement of the cable 98 between the drawworks and around the block 102.

With the hanger posts 42 and 66 uncoupled from each other by removal of bolt 48, it will be apparent that sections B and C are free to swing or pivot about the hinge connection provided by the hanger posts 22 and 76 whereby the drawworks and cable provide controlled power for raising and lowering the sections B and C with respect to the lower section A.

The folding of the derrick as shown in Fig. 4, is very advantageous for hauling the derrick as a complete unit with the skid and portable rig, especially when it is desired to transport the complete unit for short hauls, such as one well in proximity of another.

Referring now to Fig. 5 showing the upper sections of the derrick swung in a direction opposite to that disclosed in Fig. 4, the cable 98 of the drawworks extends upwardly from the drawworks 100 through the opening provided by braces 18 to the outside of the lower section A, thence around a pulley 30 and upwardly through the interior of the derrick, around the crown block 80 and again downward through the interior of the derrick, around a second pulley 30

to be fixed in dead-end position to the skid 12. With the hanger post 18 uncoupled from the hanger post 22, the upper sections B and C are free to pivot about the hinge connection provided by hanger posts 42 and 66 disposed at the top of the corner posts 6 and 8, wherein the cable will allow the derrick to be raised or lowered. This particular folded position of the derrick is advantageous when it is desired to transport the derrick separately from the skid containing the drawworks and rotary drilling structure. It will be apparent that with the derrick in this position, section B can be uncoupled from section A, as well as section C unbolted from section B to facilitate transportation of the derrick by truck or the like.

From the foregoing, it will be apparent that the derrick can be folded to either position as shown by Figs. 4 and 5, using the power of the drawworks for controlling the raising and lowering without unstringing either the crown block or the travelling block and the cable line from their drilling positions. Furthermore, it will be apparent that the pulleys 38 and 74 can be eliminated, and the cable line run over the shafts 28 and 72, however, for a more efficient operation, utilization of the pulleys is preferable.

Changes may be made in the combination and arrangement of parts as heretofore set forth in the specification and shown in the drawings, it being understood that any modification in the precise embodiment of the invention may be made within the scope of the following claims without departing from the spirit of the invention.

What I claim is:

1. In a derrick comprising a base section, a plurality of upper sections of upwardly decreasing dimensions super-imposed one upon another and supported by the base section, a hinge connection provided at the top of the base section for se-

curing the base section to an immediate upper section, a second hinge connection provided at the lower end of the base section for securing the base section to an immediate upper section, either one of said hinge connections acting as a hinge when the other one is uncoupled to allow optional pivotal movement of the upper sections with respect to the base section.

2. In a derrick comprising a base section triangularly shaped in elevation and comprising four corner posts rigidly braced by connecting ties, two of said corner posts being substantially greater in length than the remaining two posts, a pair of diagonally disposed bars connecting each of the long and short posts, an upper section disposed on the base section and comprising suitably braced long and short corner posts, a pair of diagonally disposed bars complementary with the first mentioned diagonal bars connecting the long and short posts of the upper section, means for securing the sections together at the upper and lower ends of the base section, either securing means acting as a hinge when the other one is released to allow optional directional movement of the upper section about the lower base section.

3. A derrick comprising a base section triangularly shaped in elevation, a second section having a depending triangularly shaped portion, a separable hinge connection provided at the top of the base section for securing the base section to the upper part of said depending triangular portion, a second separable hinge connection provided at the lower end of said depending portion for securing the last mentioned portion to the lower end of the base section, either one of said separable hinge connections acting as a hinge when the other one is uncoupled to allow selective pivotal movement of the second section with respect to the base section.

WALTER BRAUER.
